UNITED STATES PATENT OFFICE.

JAMES C. WHITTLE, OF JACKSON, MICHIGAN.

SPRING.

No. 845,210.

Specification of Letters Patent.

Patented Feb. 26, 1907.

Application filed February 5, 1906. Serial No. 299,519.

To all whom it may concern:

Be it known that I, JAMES C. WHITTLE, a citizen of the United States of America, residing at Jackson, in the county of Jackson 5 and State of Michigan, have invented certain new and useful Improvements in Spring Suspension, of which the following is a specification, reference being had therein to the accompanying drawings.

This invention relates to improvements in vehicle-springs; and its object is to provide means for so supporting the vehicle body or frame upon and attaching it to the spring that all sudden shocks or jars will be taken 15 up by the spring and not transmitted to the body, thus preventing undue vibration, and, further, to provide means for supporting the body or frame upon an elliptical spring at two widely-separated points.

It is also an object of the invention to provide a cheap, simple, and efficient device embodying certain other new and useful features, all as hereinafter more fully described, reference being had to the accompanying drawings, in which—

Figure 1 is a side elevation of a device embodying the invention and showing the same attached to the sill and axle of a vehicle, and Fig. 2 is a transverse vertical section of the 30 same on the line $x-x$ of Fig. 1.

As shown in the drawings, A is a side sill, B a tubular axle, and C an elliptical spring supported upon the axle and secured thereto by a clip D, all as commonly formed and embodied in automobile construction.

Ordinarily the sill is attached directly to the upper half of the elliptical spring at its center; but in my construction I make no connection at that point whatever between the 40 sill and spring, but instead secure, by means of the ordinary clip, a plate 1 to the inner face of said half of the spring, which plate is provided with downwardly-extending parallel ears 2, between which are pivoted the levers 3 and 4. Said levers, together with the levers 5 and 6, which are similarly pivotally attached to a like ear-plate secured by the clip D to the lower half of the spring, form a toggle connection between the upper and 45 lower members of said spring, and by forming said levers with forked ends they all lie in the vertical center of the spring. The forked ends of the levers 5 and 6 are extended longitudinally beyond the points of pivoted attachment of the levers 3 and 4 thereto to form 55 the arms 7, to the ends of which arms the

hangers 8 are pivotally attached. These hangers are bent or offset laterally to bring their opposite ends directly beneath the sill A and are each formed with a horizontal seat 60 9 for a coiled spring, 10, which is contained within a cup or socket member 11, attached to the sill by means of a pin 12, extending through the sill and through openings in ears on the upper end of the cup. The spring-seat on the hanger is held in alinement with the cup by a stud 13 on the seat extending upward within the cup inside the coiled spring.

When the axle is suddenly moved vertically by the vehicle-wheel coming in contact with an obstruction in the road or otherwise, the vibration caused by the shock will be wholly taken up by the springs, as it must pass from the elliptical spring through the 75 toggle-levers, hangers, and coiled springs into the cups and thence to the sill. The vertical movement is greatly reduced by the toggle-levers, and the hangers being pivotally attached to the ends of the toggle with 80 the coiled springs interposed between them and the sill vibration caused by any ordinary obstruction or from the load in the vehicle will be entirely eliminated.

The sill is supported by each elliptical 85 spring at two points some distance apart and upon the ends of the toggle-levers, which when under load exert a lesser force to draw the two parts of the elliptical spring toward each other than the load would exert if 90 placed directly on the spring, greatly minimizing the shocks, and thus a very steady easy-riding vehicle is secured. The toggle-levers by reason of this force which they exert on the spring tend to equalize the shocks and 95 prevent rebound or the excessive vertical movement of the body caused by sudden and violent vertical movement of the wheel and axle.

Having thus fully described my invention, 100 what I claim is—

1. The combination with an elliptical spring, of two levers pivotally attached at one end to the upper half of said spring near its middle, two similar levers pivotally attached at one end to the other half of the spring near its middle and pivotally connected at their opposite ends to the free ends of the other levers, vertically-disposed hangers pivotally attached to said levers near their connecting 105 pivots, and load-supporting means on each hanger.

2. The combination with an elliptical spring, of levers pivotally attached to the two members of said spring and forming a double-toggle connection between the same, 5 arms extending longitudinally from the connecting-pivots of said levers, hangers pivotally attached to the ends of said arms, coiled springs seated upon said hangers, and socket members to receive said springs adapted 10 to be attached to the vehicle-frame.
3. The combination with an elliptical spring, of downwardly-extending ears on the upper member of said spring and upwardly-extending ears on the lower member thereof, 15 two levers pivoted between each pair of ears at one end and pivoted together at their opposite ends to form a double-toggle connection between the members of the spring, said levers all lying in the vertical plane of the longitudinal center line of said spring; hangers attached to said levers and extending laterally to a point outside the vertical plane of the spring; bearing-springs seated upon the laterally-extending ends of said 20 hangers; and means adapted to be attached to the sill of a vehicle-frame to receive said springs.
4. The combination with an elliptical spring; of levers pivotally attached to the members of said spring to form a double-toggle connection between said members; hangers pivotally attached to said levers near their connecting-pivots and formed with spring-seats at their free ends; socket members adapted to be attached to a sill, coiled springs in said socket members engaging the seats on the hangers; and studs on the said seats extending upward within the socket members inside said springs.
5. In combination with the sill, an elliptical spring, a pair of levers each pivoted to one member of said spring, a second pair of levers pivoted to the other member of said spring and to said first-named levers, and 35 40 45 50 55 60 65 70 75 80 85 90 95 100 compressible means supported from each of said pivots between said pair of levers and from said sill.
6. In combination with an elliptical spring and a sill, a toggle connection between the members of said spring, an arm extended angularly from said toggle connection, and compressible means supported from said arm and engaging said sill.
7. In combination with an elliptical spring and a sill, toggle-levers connected to each of the halves of said spring, and vertically-disposed compressible means pivotally supported at one end from the connecting-point between said levers and at the opposite end pivoted to said sill.
8. In combination with an elliptical spring and a sill, a toggle connection attached thereto, a hanger supported from said connection, a spring on said hanger, and a socket member supported from said sill and receiving said spring.
9. In combination with an elliptical spring and a sill, a pair of levers pivoted together at one end and at their opposite ends pivoted to the halves of said spring, and a hanger supported from the pivotal point between said levers and having an offset part underlying said sill and compressible means between said sill and offset part of the hanger.
10. In combination with an elliptical spring and a sill arranged side by side, a movable connection between the halves of said spring, a supporting means movably related to said connection and underlying said sill, and compressible means between said sill and said supporting means.

In testimony whereof I affix my signature in presence of two witnesses.

JAMES C. WHITTLE.
